UNITED STATES PATENT OFFICE.

DANIEL H. CLOSE, OF ELMHURST, NEW YORK, ASSIGNOR TO VAN VOORHIS CLOSE, OF NEWARK, NEW JERSEY.

BRICK-RE-PRESSING MACHINE.

1,262,016.

Specification of Letters Patent.

Patented Apr. 9, 1918.

Application filed August 6, 1917. Serial No. 184,674.

To all whom it may concern:

Be it known that I, DANIEL H. CLOSE, a citizen of the United States, residing at Elmhurst, in the county of Queens and State 5 of New York, have invented certain new and useful Improvements in Brick-Re-Pressing Machines, of which the following is a specification.

This invention relates to a machine for 10 repressing bricks. Such machines are of course in use as it is common practice to repress bricks. But all devices of this character that I have knowledge of are located in a fixed position, the pallets are taken 15 from the drying racks, loaded upon a truck, moved to the repressing machine and the bricks then lifted by hand from the pallets and placed in the molds, then after being repressed they are removed by hand, re- 20 placed on the pallets and wheeled back to the racks.

My invention is designed to save as much of the time and labor involved in this operation as possible.

25 The invention consists in a repressing machine mounted upon a movable frame which is adapted to travel along a track between the drying racks, being stopped at any suitable place. The pallets, with from 30 six to ten bricks thereon, are placed on the machine, the pallets are automatically advanced to the molds, all of the bricks on the pallet removed at one time and placed automatically in the molds, and the pallet then 35 lifted upwardly and transferred by a suitable conveyer to the opposite side of the molds, and the repressed bricks delivered to it. The pallet with the repressed bricks is then moved to the front of the machine, 40 and lifted therefrom by hand and replaced in the racks. The only hand operation employed is the lifting of the pallets from the racks to the machine and from the machine back to the racks.

45 The invention also consists in the novel features of construction hereinafter described, pointed out in the claims, and shown in the accompanying drawings in which:—

Figure 1 is a side elevation, parts being 50 broken away.

Fig. 2 is a horizontal section on the line 2—2 of Fig. 1.

Fig. 3 is an end elevation.

Fig. 4 is a side elevation, partly in section, and showing details of a carriage, and carriage releasing and moving devices.

Fig. 5 is a section on the line 5—5 of Fig. 4.

Fig. 6 is a section on the line 6—6 of Fig. 4.

It will be obvious that in a device of this kind many of the parts employed are not of themselves new, and may be changed without in any way affecting my invention.

In order therefore to illustrate the invention as clearly as possible I have omitted some of these features, as they would, if included, hide parts that relate directly to the invention, would confuse the drawings, and would of themselves add nothing to the disclosure. This relates especially to the motor power employed, and the means for transmitting power from one part to another, either by belts, chains or gears. The device as a whole is intended to be operated 75 by either an electric motor or a gasoline engine. If with motor it will be supplied with current from an overhead trolley. If by gasoline engine no wires will be required. It is obvious that neither the electric motor, the trolley, or the engine form a part 80 of the invention, and they are therefore not shown.

In the drawings, 1 designates a suitable track which is placed along the alleys between the drying racks, also not shown, and on said track runs a wheeled frame 2 comprising the uprights 3.

These support a suitable table 4 provided at its center with a transversely extending 90 offset or jog 5.

The table is practically an open frame and at its rear end portion are transverse shafts 6 provided with wheels 7, on each side of the table, and belts 8.

At the forward end are similar wheels 11, shafts 10 and belts 12. The belts 8 and 12 form conveyers at the rear and front of the tables respectively.

In the offset portion of the table are 100 molds 13 provided with lower plungers 14 which work in the molds, and the molds are separated by vertical partitions 15. These partitions extend above the mold tops and

form also guides for the bricks as they enter the molds, the plungers forming the mold bottoms. The plungers are actuated by rods 16 engaged by cams 17 on a shaft 18. This shaft can be run either by pulley and belt from the engine or motor, not shown, or by a gear 19, which can mesh with any suitable gear train from the motor or engine, not shown.

- 10 Upper coöperating plungers 20 are carried by a frame 22, and actuated by a rod 23, in the usual manner, which rod may be operated in any manner from shaft 18, as by an eccentric 23^a. The use of the lower and upper plungers in brick pressing machines is not claimed as new.

When the bricks are placed in the racks they are held on pallets 24. These pallets are of greater length than the width of the 20 table. They usually hold from six to ten bricks, and there will be as many molds and plungers in both upper and lower sets as there are bricks on the pallets. In the drawings I have illustrated a machine having 25 six of the molds and designed to work with pallets each of which holds six bricks. But the number is not material.

When the pallets are lifted from the rack they are placed one at a time transversely 30 across the belts 8, and are conveyed by the belts to the offset portion 5 which acts as a stop for the pallets. This offset is just equal to the thickness of the pallets so that the bricks 25 will move smoothly from said 35 pallets to the molds.

To automatically accomplish this movement I employ a grooved carriage frame 26 in which reciprocates a carriage 27 in the form of a rectangular frame, so the upper 40 plungers can work through it. Within the frame forming the carriage are pivoted brick pushing leaves 28 the swinging movement of which rearwardly is limited by stops 29, these leaves depending suffi- 45 ciently to engage the bricks but to clear the tops of the mold partitions. At each forward movement of the carriage all the bricks in the mold will be pushed forwardly onto a pallet on the forward conveyer belts 12, 50 and a new lot of bricks will be pushed into the molds from a pallet on the rear conveyer belts 8. During rear movement of the carriage the leaves will drag freely over the bricks.

55 To provide for passing the pallets around the molds the following mechanism is employed:

Cog chain wheels 30 which may mesh with the gears 19 on shaft 18, or in case said 60 shaft is driven by pulley and belt, with suitable gears replacing gears 19, drive chains 32 running over idlers 31, four of which are carried by an overhead bracket 33 supported by the frame 22.

65 There are two of these chains, one on

each side of the table and they carry small pivoted hangers or lifts 34, mounted to hang horizontally, and as these lifts travel upwardly next the rear portion of the table they will engage the projecting ends of the 70 pallet adjacent the molds and lifting it will carry it over the upper plungers, through the framing 22 and bring it down to the belts 12, where it will be disengaged. They are so timed and spaced that they will take a pallet from the rear conveyer just after the carriage has cleared it of bricks, and will deposit a pallet on the front conveyer in time to receive a new supply of re-pressed bricks.

75 The means for operating the carriage is one of the essential features of my invention. A shaft 35 with pulley 36 driven by a belt 37, from shaft 18 has on each end portion a loose wheel 38, grooved for a cable, and a keyed wheel 39. As these parts are duplicated on each side of the table, a description of the mechanism on one side will be sufficient.

80 A cam block 40 is secured to the periphery of the wheel 39, and a pin 41 is secured on the periphery of the grooved wheel 38, which is of less diameter than the wheel 39. On the keyed wheel 39 is placed a spring pressed pin 42 which works through a 85 laterally extending bracket 43 carried by the keyed wheel. The spring normally presses this pin radially outwardly so that it would clear the pin 41. But a curved metal arm 44 is fastened to the underside 1 of the table and incloses about one half of the periphery of the loose wheel 38.

86 A cable 38^a is secured to the periphery of the wheel 38 working in the groove, and runs over a guide wheel 45 to a block 46 1 carried by the rear end of the carriage.

To this block is also connected a catch 47 pivoted to the lower end of the block, so that on forward movement of the carriage it will ride over and lock against a stop 47^a 1 on the offset portion of the table. The carriage is released by the lifting of said catch by a pin or rod 47^b. This rod is normally pressed downwardly by a coil spring 48, the rod being carried by a pivoted bracket 49 1 which has an arm 50 extending into the path of the block 40.

It will be obvious from this description and the drawings that during rotation of the wheel 39 the pin 42 will be brought under the curved portion of the iron arm 44 and be forced down or inwardly so as to engage the pin 41 on wheel 38. This rotates the wheel 38 and winds the cable 38^a partly thereon drawing the carriage forward and as it locks by engagement of the catch 47 with the stop 47^a the pin 42 passes out from under the arm 44 and rotation of the wheel 38 stops.

90 The carriage remains locked against rear 1

movement until cam block 40 engages the arm 50 thereby throwing up the rod 47^b and disengaging the pivoted catch 47.

The carriage is then drawn rearwardly 5 by cable 51 running over idle pulley 52 and the weight 53.

To prevent a pallet being pushed or pulled from under the bricks during reloading stop pins 54 carried by pivoted brackets 10 55 are employed. These brackets may be tripped at the proper time in any desired manner, as by having their rear ends extend into the path of the cams on the shaft 18, or they can be engaged and tripped by the 15 hangers carried by the chains 32. After a reloaded pallet has been conveyed to the front end of the table it is removed by hand and replaced in the drying racks.

I have omitted such details of power 20 transmission in order not to cover up and obscure features of the invention, as the arrangement of gear and belts etc. are simply matters of mechanical detail and are not considered as involving invention, or as 25 forming any part of my actual invention.

I do not therefore desire to be limited to any particular means of moving the truck or platform 2 along the track, or of operating the plungers or driving the conveyers, 30 all of this transmission mechanism being old and well known.

What I claim is:—

1. In a machine of the kind described, a series of molds, conveyers arranged on opposite sides of said molds, both conveyers 35 traveling in the same direction, common means for removing bricks from a pallet on one of said conveyers and for transferring bricks from the molds to a pallet on the other conveyer, and means for transferring 40 the pallets from one conveyer to the other.

2. In a machine of the kind described, a table, conveyers arranged on opposite end portions of the table, a series of molds arranged across the center of the table, a reciprocating carriage, means for moving said carriage, and hinged leaves carried by the carriage and adapted to move bricks from one conveyer to the molds, and from the 50 molds to the other conveyer.

3. The combination with a series of pressing devices, of conveyers adapted to carry pallets to and from said pressing devices, and chains movable on opposite sides of the 55 conveyers and at right angles thereto, for lifting the pallets and transferring them over the pressing devices from one conveyer to the other.

4. In a machine of the kind described, 60 brick pressing molds, means for moving pallets to a point adjacent one side of the pressing devices, means for moving pallets away from the opposite side of the pressing device, means for automatically transferring 65 pallets from one side of the pressing devices

to the other, said means comprising a carriage, and means for moving, locking and releasing the carriage at predetermined times.

5. A brick repressing machine comprising a series of molds, means for conveying pallets to and from the molds, a carriage movable above the molds and above one of said conveyers, hinged leaves carried by the carriage and adapted to engage and push 70 the bricks from the molds to a pallet and from a pallet to the molds as the carriage moves forwardly, and means for moving the carriage comprising a driven wheel, an idle wheel, a cable secured to the rear end of the carriage and to the idle wheel, a curved arm extending partly around the idle wheel, a pin on the idle wheel, a spring pressed pin on the driven wheel, said pin when engaged by the arm being pressed into alignment 75 with the pin on the idle wheel, and means for drawing the carriage rearwardly.

6. A machine of the kind described comprising a table having a central, transverse offset portion, a series of brick repressing 80 molds carried thereby, conveyers on opposite sides of the offset portion, both conveyers traveling in the same direction, and adapted to carry pallets to and from said molds, the offset in the table acting as a stop 85 for the pallets on one of the conveyers and being equal to the thickness of the pallet, a reciprocating carriage having means for simultaneously engaging bricks on a stopped pallet and on the mold, and moving said 90 bricks respectively from the pallet to the mold and from the mold to a new pallet, means for regulating movement of the carriage, and traveling chains adapted to pick up and transfer empty pallets from one side 95 of the molds to the other.

7. In a device of the kind described comprising conveyers for brick pallets, traveling chains passing upwardly on opposite sides of one conveyer and downwardly on opposite sides of the other conveyer, and pivoted hangers carried by the chains and adapted to engage and lift pallets as said hangers pass upwardly by one of the conveyers, and to deposit said pallets on the other conveyer.

8. In a device of the kind described, a series of brick pressing molds, conveyers on opposite sides of the molds, both conveyers moving in the same direction, means for 120 lifting pallets from one conveyer over said molds to the other conveyer, means for moving the bricks from a pallet to the molds and from the molds to another pallet, means for locking the last mentioned pallet against 125 movement while bricks are being pushed thereon, and means for automatically regulating the transfer of the bricks from a pallet to the molds and from the molds to a pallet.

9. In a device of the kind described, a carriage reciprocating device comprising a fast and a loose wheel, a cable secured to the carriage and to said loose wheel, means connecting the fast wheel to the loose wheel during a portion of the rotation of the first mentioned wheel, a catch carried by the carriage adapted to lock it in forward position, a rod adapted to trip said catch, means carried by and actuated by the fast wheel for moving said rod, and means including a weight for returning the carriage to normal position when released.

In testimony whereof I affix my signature.

DANIEL H. CLOSE.
